UNITED STATES PATENT OFFICE.

PATRICK GOODMAN, OF BROOKLYN, NEW YORK.

GAS-MAIN STOPPER.

Application filed August 30, 1924. Serial No. 735,196.

To all whom it may concern:

Be it known that I, PATRICK GOODMAN, a citizen of the United States of America, and a resident of the city of New York, borough 5 of Brooklyn, in the county of Kings and State of New York, have invented a new and Improved Gas-Main Stopper, of which the following is a description.

The present invention is an improvement on 10 the gas-main stoppers forming the subject matter of United States Patent Number 940,-458, granted to me November 16, 1909, and of Patent Number 960,086, granted to me May 31, 1910. In said patents the assemblage 15 comprises a collapsible frame having a diaphragm which is adapted to be passed through an opening in the side of the gas-main and then expanded in the main to cut off the flow of gas, said frame having handle bars to extend through the opening to the 20 exterior and having means arranged to force the handle bars in opposite directions to lock the stopper in place.

The present invention more particularly 25 relates to means for forcing the diaphragm and its frame in opposite directions to lock the stopper in place and forming a complete closure of the gas main.

Reference is to be had to the accompanying 30 drawings forming a part of this specification, it being understood that the drawings are merely illustrative of one example of the invention.

Figure 1 is a side view of a gas-main 35 stopper embodying my improvements, the stopper being shown locked in position in the main, and the main in longitudinal central vertical section;

Figure 2 is a vertical section substantially 40 on the line 2—2 of Figure 1;

Figure 3 is an inner face view of the stopper when collapsed, showing the handle-bars in section.

Figure 4 is an enlarged view in vertical 45 section of the sleeve applied to one handle bar, the latter shown in side elevation.

The stopper proper in which the present 50 improvements are embodied has the same general assemblage as the stoppers in my aforementioned patents. Said stopper embodies generally in its construction a collapsible spring frame 10 covered by a yielding packing and having a flexible diaphragm 11, which is stretched across the frame in 55 circular form by exerting pressure on the

frame at diametrically opposite points. At these points the frame is provided with pivotally connected telescoping members 12 and 12^a, bridging the diaphragm, and pivotally connected handle-bars 13 and 14, each bar being provided with suitable hand-grips 15 and 115. A hook designated generally by the numeral 16 is provided, having a threaded shank extending through the hand-grip 115 and provided with a tightening nut 17 and a set nut 18. The hooked end 19 of the hook 16 is adapted to engage beneath an oblique overhanging lug 20 on a sleeve 21 fitted on the handle-bar 14. Depending from the sleeve 21 is a bracket 23 having a foot 24 at the lower end adapted to engage the gas-main at the opening formed therein for the insertion of the stopper.

With the described arrangement, when the sleeve 21 is positioned on the handle-bar 14 75 with the foot 24 engaging the gas-main at the edge of the opening, the hook 19 is engaged beneath the lug 20. It is to be observed that said lug 20 is at the front of the sleeve 21 and the sleeve is so disposed as to 80 position the said lug at the front of the handle-bar 14. The said disposition of the lug allows complete clearance for the movement of the handle-bar 13 relatively to the handle-bar 14 for exerting a force against the 85 frame 10 at the top to jamb the frame gas-tight in the main. In addition, the provision of the lug 20 at the front of sleeve 21 and handle-bar 14 more effectively applies the force developed by turning the nut 17 90 forwardly on the hook 16 and it furthermore promotes convenience in the manipulation of the several elements.

I would state in conclusion that while the 95 illustrated example constitutes a practical embodiment of my invention, I do not limit myself strictly to the exact details herein illustrated, since, manifestly, the same can be considerably varied without departure from the spirit of the invention as defined in 100 the appended claims.

Having thus described my invention, I claim:

1. A gas-main stopper having handle-bars pivotally connected at substantially diametrically opposite points on said stopper, a sleeve adjustable along one of the handle-bars and provided with means to engage a gas-main at an opening therein, means to exert pressure on the other handle-bar to lock 110

the stopper in the main, and means at the front of the sleeve engageable by the means to exert pressure on the second handle-bar.

2. A gas-main stopper having handle-bars pivotally connected thereto at substantially diametrically opposite points, a hook adjustably carried by one of the handle-bars, and means at the front of the other handle-bar to be engaged by said hook.
- 5 3. A gas-main stopper having handle-bars

pivotally connected thereto, a hook having a threaded shank adjustably engaging one of said handle-bars, a sleeve on the other of said handle-bars, said sleeve having a foot integral therewith to engage a gas-main at an opening therein, said sleeve furthermore having a lug at the front thereof to be engaged by said hook. 15

PATRICK GOODMAN.
